US0D1103803S

(12) **United States Design Patent** (10) Patent No.: **US D1,103,803 S**
(45) Date of Patent: ** Dec. 2, 2025

(54) **FLOWMETER**

(71) Applicant: **PIUSI S.P.A.**, Suzzara (IT)

(72) Inventor: **Otto Varini**, Suzzara (IT)

(73) Assignee: **PIUSI S.P.A.**, Suzzara (IT)

(**) Term: **15 Years**

(21) Appl. No.: **29/829,399**

(22) Filed: **Mar. 4, 2022**

Related U.S. Application Data

(62) Division of application No. 29/716,438, filed on Dec. 10, 2019, now Pat. No. Des. 960,737.

(30) **Foreign Application Priority Data**

Jun. 10, 2019 (EM) 006573168
